US0D1075597S

(12) **United States Design Patent** (10) Patent No.: **US D1,075,597 S**
(45) Date of Patent: ** May 20, 2025

(54) **JOYSTICK FOR TRACTOR**

(71) Applicant: **LS Mtron Ltd.**, Anyang-si (KR)

(72) Inventors: **Sung Hee Park**, Anyang-si (KR); **Ho Jung Kim**, Anyang-si (KR)

(73) Assignee: **LS MTRON LTD.**, Anyang-si (KR)

(**) Term: **15 Years**

(21) Appl. No.: **29/894,840**

(22) Filed: **Jun. 14, 2023**

(30) **Foreign Application Priority Data**

Dec. 15, 2022 (KR) 30-2022-0052862

(51) **LOC (15) Cl.** **12-16**

(52) **U.S. Cl.**

USPC **D12/174**

(58) **Field of Classification Search**

USPC D12/174, 179, 195, 220, 415;
D14/412-416; D8/300-303, 307

CPC F16H 63/42; F16H 59/0278

(57) **CLAIM**

The ornamental design for a joystick for tractor as shown and described herein.

DESCRIPTION

FIG. 1 is a perspective view of a joystick for tractor showing the new design;

FIG. 2 is a front view thereof;

FIG. 3 is a rear view thereof based on FIG. 2;

FIG. 4 is a left-side view thereof based on FIG. 2;

FIG. 5 is a right-side view thereof based on FIG. 2;

FIG. 6 is a top plan view thereof based on FIG. 2; and,

FIG. 7 is a bottom view thereof based on FIG. 2.

1 Claim, 7 Drawing Sheets
